POTENTIOMETER

Henry M. Dressel, Chicago, Ill., assignor to Oak
Mfg. Co., a corporation of Illinois

Application November 14, 1940, Serial No. 365,665

3 Claims. (Cl. 179—109.41)

This invention relates to a potentiometer and while of general application is particularly adapted for use where rapid variations in potential are to be produced. In particular this invention is useful for translating sound waves into electrical impulses such as in pick-ups for sound reproduction from wax records, microphones, vibration indicators, etc.

In order that rapid variations of mechanical movements may be transformed to potential variations faithfully, it is highly desirable that the system have as little mechanical resonance and resistance effects as possible. The advisability of eliminating the former effects are obvious and need not be further discussed. However, the mechanical resistance characteristics of a device of this character when used for sound reproduction from wax records is important from a practical angle.

Inasmuch as a pick-up is an inertia device, it is evident that if the mechanical resistance of the movable portion of the pick-up is great then the weight of the entire device must be sufficiently great to permit the pick-up to operate. Such a weight results in a substantial pressure upon the needle point in the record groove and thus makes for rapid wear and breakdown of the record grooves. It is clear therefore that if a light needle pressure is to be used, then it is necessary to make the movable element of the pick-up highly responsive to vibration.

It is also highly desirable to have a translating device such as a pick-up or microphone feed directly into the control electrode of a vacuum tube amplifier. Thus coupling transformers are eliminated. For all practical purposes, a connection of this character looks into an impedance amounting in practice to about one megohm. In order to provide proper potentiometer action, it is necessary therefore that the effective range of resistance over which the potentiometer operates be not more than about one-fifth of the resistance into which said potentiometer looks. With a translating device connected directly to the grid of a vacuum tube, it would therefore be highly advisable to have the potentiometer electrode operate over a resistance of the order of about two hundred thousand ohms. This may be larger or smaller under various conditions.

For practical operation of a translating device with an amplifier, it is desirable that the potentiometer varies the potential of the control electrode over a range of about one or two volts. In other words, therefore, the potentiometer cur-

rent involved is of the order of several microamperes.

From a commercial angle, it is desirable that a translating device be simple, easy and cheap to manufacture, be rugged and have a long useful life. The invention hereinafter disclosed fulfills these requirements to a remarkable degree while satisfying the technical requirements.

In general this invention provides a potentiometer wherein the resistance element is a body of liquid. For stable operation and long life it is highly desirable to prevent electrical decomposition of the liquid by virtue of the passage of current therethrough. This, of course, is true if direct currents are impressed upon the potentiometer. In the case of alternating currents, however, little if any decomposition will result. For use in a phonograph, a potentiometer pick-up is preferably connected to a suitable source of direct current, this being readily available. A high frequency alternating current may be used with the record variations being used for modulating in the event that alternating currents are desired.

25 A pair of spaced electrodes are disposed in the liquid and upon these electrodes there is impressed the difference of potential previously referred to. The potentiometer electrode is disposed between said spaced electrodes in said liquid. By moving the potentiometer electrode between said spaced electrodes, the potential of said potentiometer electrode is varied as it travels along the potential gradient between the spaced electrodes.

30 35 From a mechanical angle and in order to avoid any fine dimensions and work, it is preferred to space the electrodes a distance apart of the order of about one quarter or one-eighth of an inch. This of course may be greatly varied. Considering the amount of motion of the potentiometer electrode when actuated by a record needle operating in a groove or when actuated by a microphone diaphragm, it will be found that potential variations of the order of about one or two volts are impressed upon the potentiometer electrode when the potential difference between the spaced electrode is about two or three hundred volts with the spacing given above. It is thus evident that for satisfactory operation under the above conditions, liquids having a substantially high resistance must be used.

40 45 50 55 As a general rule, liquid insulators such as mineral oil in pure form have too high a resistance and are not suitable. Obviously the ordinary electrolytes have too low a resistance.

I have determined that organic liquids having an OH radical may be suitable. Thus the various alcohols have desirable characteristics. These alcohols are preferably used as supplied in commercially pure concentrated form. Thus I have successfully used methyl alcohol, ethyl alcohol, butyl, amyl and other higher alcohols. Mixtures of these alcohols may also be used. Polyhydric alcohols such as ethylene glycol or glycerine may also be used. It is also possible to dissolve some mineral oils in one or more of these alcohols and adjust the resistance characteristics.

It is preferred to use a high boiling liquid so that a device may be sealed without building up excessive vapor pressures under normal room conditions. However, any liquid having a suitable resistance may be used.

It is preferred to have the opposed surface area of the spaced electrodes as small as possible. Thus current flow is reduced to a minimum and concentrated. The potentiometer electrode may also have a minimum area transverse to the potential gradients spanning the spaced electrodes. While a fine potentiometer electrode may be used, I prefer to use a potentiometer electrode having a substantial area lying in a plane parallel to the line joining the spaced electrodes. In effect such an electrode serves to concentrate practically all of the potential gradients in itself and creates two separate series connected liquid paths. Thus the movement of such an electrode results in a maximum variation of potential. It is clear that if a potentiometer electrode does not have substantially all of the potential gradients passing through it between the spaced electrodes that any movement of such a potentiometer electrode will not result in the greatest change of potential since all liquid shunt paths will be unaffected. However, under some conditions it may be desirable to have a potentiometer function in this manner and it is to be clearly understood that the potentiometer electrode may be as large or small as desirable.

In the event that a potentiometer electrode is used having a substantial area as described above, vibration of the electrode between the spaced electrodes, will result in variations of potential. A mechanical system of this order has weak resonance characteristics and very little resistance so long as the movable electrode has practically no surface transverse to the line of motion. Of course, if liquid damping is desirable then some fins transverse to the line of motion may be provided.

The invention will now be described in detail in connection with the drawing.

Figure 1 is a sectional view of a pick-up;

Fig. 2 is a section along 2-2 of Fig. 1; and

Fig. 3 is a circuit diagram showing how the pick-up may be connected.

While a phonograph pick-up has been illustrated as a specific example, it is clear that in place of the needle a diaphragm may be substituted and thus a microphone may be had.

Referring to the drawing, a liquid container or casing 10 may be provided. This casing has a bottom 11, sides 12 and 13, and front and rear ends 14 and 15. The container may be of any suitable material, preferably an insulator not affected by the liquid content. Thus glass, Bakelite, hard rubber or any plastic may be suitable. End wall 15 has molded or sealed therein a pair of stiff wire electrodes 17 and 18. These electrodes may be of copper, brass, tungsten or even

carbon. However, I have found that platinum or gold remain clean and I prefer them.

In order to reduce electrode exposure to a minimum, the casing material may be extended as at 19 and 20 inwardly from the wall. The same effect may be obtained by rubber sleeves pulled over the wires. Electrodes 17 and 18 extend through casing wall 15 to form terminals. As is clearly evident, electrodes 17 and 18 extend inwardly into the space enclosed by the casing. While shown as parallel, their relative disposition is of no great importance. Preferably they lie in a plane parallel to bottom 11.

The front end of casing 10 has a circular aperture 22 in bottom 11. The wall material has its thickness built up there to give a satisfactory supporting surface. Within aperture 22 is a sealing plug 23 of soft rubber through which passes the vertical part 24 of a vibratable needle assembly.

Part 24 extends upwardly and has an upper portion 25 provided with a threaded tip 26 extending into a suitable well in 24 so that both 24 and 25 may be screwed together. Upper part 25 extends through an aperture 30 in cover plate 31 and has a thrust ring portion 32 adapted to rest on cover plate 31. A bearing cup 33 fits over the extreme upper tip of part 25 to enclose the same. It is understood of course that the various seals are liquid tight.

Tightly clamped between post portions 24 and 25 is a movable flat electrode 35 preferably lying in the plane determined by electrodes 17 and 18 and has substantial width in comparison to the distance between electrodes 17 and 18. There is no exact ratio and the only necessity is to insure the convergence of substantially all potential gradients thereto. Small ears 36 and 37 extend adjacent front wall 14 and are designed to limit the movement of the movable electrode to prevent direct contact with either of the fixed electrodes.

Vertical part 24 of the needle assembly carries an insulating section 39 to which is attached a needle holder 40 for clamping a phonograph needle 41. A jewel may be permanently fixed instead if desired. A lead 42 of fine wire is soldered to part 24.

The container is filled with a liquid as described above and cover 31 is sealed in position in any suitable manner. The pick-up may be supported on a tone arm in any desired fashion.

One example of a satisfactory liquid is a mixture of octyl and butyl alcohols. The octyl alcohol has too high a resistance while the butyl has too low a resistance. A mixture of the two in proportions of one-third butyl and two-thirds octyl operates satisfactorily. With this mixture I have used potentials of about 225 volts and obtained satisfactory pick-up potential changes.

Preferably, the resistance to turning of part 24 is slight. In fact rigid bearings for part 24 may be provided and plug 23 may be designed to furnish sealing with slight resistance to turning movement of part 24. It is clear that some zero position restoring force is necessary but this may be very small. The weight on the needle point is preferably reduced to a low value, just enough to impart movement to electrode 30 and feed the pick-up along the spiral groove.

Referring now to Fig. 3, electrode 17 may be grounded while electrode 18 is connected through a resistance 50 to any suitable source of direct potential as point 51. Resistance 50 is for filter purposes and in practice may have a value of

several hundred thousand ohms. A condenser 52 is connected from electrode 18 to ground to complete filtering.

Potentiometer electrode 33 is connected through a blocking condenser 55 to control grid 56 of a vacuum tube amplifier 57. Condenser 55 is merely to isolate the direct current from control grid 56 and may have a value of about .01 mf. to pass audio frequencies. A grid resistor 59 of about 1 megohm (or whatever value amplifier 57 requires) is connected from grid 56 to ground. Cathode 51 is maintained at a suitable positive potential above ground by bias resistor 52 shunted by a by-pass condenser 53 as is customary. As shown here, the amplifier 57 has an accelerating anode 54 connected to point 51 while the anode proper 55 is connected to point 51 through a resistor 56. Any other amplifier circuit may be provided.

As previously indicated, the potential across electrodes 17 and 18 may be of the order of 150 or 200 volts. Voltage variations of the order of 1 volt may be obtained at the movable electrode 33. Of course, the average ratio and distances between the fixed electrodes will also determine the variations in voltage.

What is claimed is:

1. A potentiometer comprising a liquid having sensible continuous conductivity, a pair of spaced electrodes immersed in said liquid, said electrodes being relatively fixed and having a small effective

area and being separated by a distance in the liquid great in comparison to any transverse electrode dimension, said electrodes being adapted to have a substantial potential difference impressed therebetween to cause some current flow through said liquid, and a potentiometer electrode between said fixed electrodes, said potentiometer electrode being movable along straight lines between said spaced electrodes, said potentiometer electrode having an effective electrode area disposed along lines connecting said spaced electrodes with the area being much greater than the area of the first-named electrodes, the liquid resistance being high enough and said potentiometer electrode area being great enough so said potentiometer electrode concentrates substantially all the potential gradients passing through the liquid in itself to create two substantially separate series connected liquid paths.

2. A translating means comprising the potentiometer of claim 1 wherein means are provided for moving said potentiometer electrode in accordance with mechanical movements to be translated.

3. A phonograph pick-up comprising the potentiometer of claim 1 wherein a reproducing stylus is provided and wherein means are provided for impressing the stylus vibrations upon said potentiometer electrode.
